[57] CLAIM

The ornamental design for a medical waste disposal container lid, as shown and described.

DESCRIPTION

FIG. 1 is a top plan view of a medical waste disposal container lid showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a side elevational view thereof, the opposite side elevational view being a mere image of that shown;

FIG. 7 is a top perspective view thereof with its lid in open condition; and,

FIG. 8 is a top perspective view thereof, showing the lid in a partially folded position.

FIG. 1

FIG. 2

FIG. 3

FIG. 4

FIG. 5

FIG. 6

FIG. 7

FIG. 8
